HANDLE FOR SLIDING DOOR

Harold L. Fells, Roslyn Heights, N.Y., assignor to Allen-Stevens Corp., Woodside, N.Y., a corporation of New York

Filed Jan. 13, 1964, Ser. No. 78,164

Term of patent 14 years

(Cl. D10—8)

Fig. 1.

Fig. 2.

Fig. 3.

Fig. 4.

Fig. 5.

FIG. 1 is a perspective view of a handle for sliding door showing my new design;

FIG. 2 is a side elevational view thereof;

FIG. 3 is a front elevational view;

FIG. 4 is an elevational view of the side opposite that shown in FIG. 2; and

FIG. 5 is a bottom plan view thereof.

The side opposite that seen in FIGS. 1 and 3 is conventionally plain.

I claim:

The ornamental design for a handle for sliding door, as shown.
